DESIGN FOR A CUTICLE REMOVER

John N. Whitehouse, Camden, N. J.

Application July 30, 1938, Serial No. 78,982

Term of patent 14 years

To all whom it may concern:

Be it known that I, John N. Whitehouse, a citizen of the United States and a resident of Camden, in the county of Camden, State of New Jersey, have invented a new, original, and ornamental Design for Cuticle Remover, of which the following is a specification, reference being had to the accompanying drawing, forming part thereof.

Fig. 1 is a front elevational view of a cuticle remover showing my new design; and

Fig. 2 is a side elevational view thereof.

I claim:

The ornamental design for a cuticle remover, substantially as shown.

JOHN N. WHITEHOUSE.
